CLAIM

The ornamental design for a LED panel light, as shown and described.

DESCRIPTION

FIG. 1 is a front elevational view of a second embodiment of a LED panel light of our new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a perspective view thereof;
FIG. 8 is another perspective view thereof;
FIG. 9 is an enlarged view of portion 9 shown in FIG. 1; and,
FIG. 10 is an enlarged view of portion 10 shown in FIG. 7.
The broken lines showing portions of the LED panel light that form no part of the claimed design.
The dash-dot lines in the drawings do not form part of the claimed design.

1 Claim, 8 Drawing Sheets
